UNITED STATES PATENT OFFICE.

WILLIAM HARNACH, OF NEW YORK, N. Y.

IMPROVEMENT IN TASSELS FOR CANES AND UMBRELLAS.

Specification forming part of Letters Patent No. **140,825**, dated July 15, 1873; application filed May 5, 1873.

To all whom it may concern:

Be it known that I, WILLIAM HARNACH, of the city, county, and State of New York, have invented a new and Improved Cane and Umbrella Tassel, of which the following is a specification:

Cane and umbrella tassels have, up to this time, been wholly made of leather, by rolling up a strip of leather slitted nearly across from side to side to form the strings for the tassel, braiding a string around the roll or head formed by the unslit portion, and attaching the string or strings by which the tassel is suspended. Now, I have contrived how to make a neater and cheaper tassel of this character than can thus be made of leather, by making this slitted strip of paper colored like the color of leather, and varnished with a water-proof varnish. The appearance is better, because the surface is smoother, the substance more compact, and the color brighter. It is equally if not more durable than leather, and is considerably cheaper.

Figure 1 is a side elevation of a cane-tassel constructed according to my invention; and Fig. 2 is a side elevation of a portion of the slitted paper strip of which the roll of strings is made.

A represents the said paper strip of which the strings of the tassel are formed by slitting it, as shown. B represents the braid of leather strings applied to the head of the roll; and C represents the suspending-strings.

Having thus described my invention, I claim as new, and desire to secure by Letters Patent—

As a new article of manufacture, the tassel, consisting of the slitted paper A, covered with water-proof and leather-colored varnish, and combined with the leather braid B, as and for the purpose described.

WM. HARNACH.
